REVOLVING CONNECTER

Hjalmar Asklund, Uddevalla, Sweden

Application July 13, 1934, Serial No. 735,023
In Sweden July 3, 1933

4 Claims. (Cl. 173—324)

My invention relates to a connector for electric cords and the like, which has for its object to prevent twisting of the same. As is known such twisting often occurs in cords for example of 5 telephones, irons, cord lamps and other apparatus connected by means of cords.

According to my invention I provide between the cord and the electric apparatus or between two cords a swivelling coupling or connector comprising two contact carrying members, which may be turned relatively to each other and are provided with contacts, for example in the shape of contact rings so disposed that during the 10 revolving movement each of the contacts of one contact carrying member always is in engagement with a corresponding contact of the other contact carrying member, the contacts being furthermore connected with terminal screws, plug contacts, contact sleeves or other connecting devices, which serve to connect a cord to one of 15 the contact carrying members and to connect a cord or an electric apparatus to the other contact carrying member.

Preferably one contact carrying member is shaped as a substantially cylindrical outer casing, which is divided into two halves along an axial plane and the interior of which is provided with bands of metal connected to contact sleeves, annular metal rings being rotatably disposed in the said bands on an interior cylindrical contact carrying member, which thus may be turned relatively to the outer casing and which also is provided with contact sleeves or the like for connecting a cord.

If desired, ball bearings may be provided between the contacts of the two contact carrying members so as to conduct the current and to reduce the bearing friction. Instead of ball bearings also spring washers may be disposed between the contacts.

The accompanying drawing shows embodiments of the invention by way of example.

Figure 1 shows a coupling or connector, in which one contact carrying member consists of an outer cylindrical casing 1 of "Bakelite" or other insulating material, which is provided with a closed head 2 at one end and with inwardly curved walls 3 at the other end. The casing is divided into two halves along an axial section, the said two halves being held together by means of screws 4. The inside of the casing is provided with several annular recesses, in which semi-circular or segmental metal bands 5 are embedded at the surface. Bearing rings 6 of metal are placed onto the bands 5 and serve as contacts

bearing against the metal bands 5. By means of conducting wires 7 embedded in the wall of the casing the metal bands 5 are each connected with a contact embedded in the head 2 adjacent to one of the sockets 8 adapted to receive a pin of 5 a complementary coupling. The other contact carrying member consists of a cylinder 9 of "Bakelite" or other insulating material and is disposed coaxially within the outer casing 1. In the cylinder 9 metal bands 10 are embedded at the surface 10 against which bear contact rings 11 having angular cross section, which at the revolving of the inner contact carrying member relatively to the outer one always are in touch with the said bearing rings 6, which have a convex or rounded resting- and contact surface. In the inner cylinder are further embedded conducting wires 12, which connect each of the bands 10 with its contact sleeve 13. The four conductors of the cord 14 are introduced into the contact sleeves 13 and 20 held in their positions by means of clamping screws 15. Each pair of the mutually turnable contact rings 6, 11 is insulated from the next pair by means of discs 16 of mica or other suitable insulating material. The lower end of the inner 25 contact carrying member, which end is provided with contact sleeves, is widened to support the nearest metal bearing 11, and the other end is threaded and provided with a nut 17 having a spring washer 18, which nut serves for tightening 30 the contacts and holding the whole together. Instead of the threads being provided on the contact carrying member 9 itself, which consists of insulating material, a screw bolt may be embedded in the contact carrying member 9, on to 35 which the nut 17 is screwed, by which arrangement a greater strength is obtained.

Instead of the bands 5, 10 also short contacts or contact segments, which extend only along part of the circumference, may be embedded into 40 the contact carrying members.

Figure 2 shows another embodiment of the contacts. In this case they are made in the shape of discs 19, 20 between which ball bearings 21 are disposed. By means of the ball bearings, 45 which also serve to conduct the current, the advantage is obtained that the bearing friction is reduced, which is of great importance in certain cases, when it is desired that the revolving connection shall move as easily as possible. 50

Having now described my invention, what I claim as new and desire to secure by Letters Patent is:

1. A swivelling coupling for electrical conductors comprising cylindrical coaxial insulating 55

members adapted to be placed one within the other in spaced relation and relatively rotatable on a common axis, the outer of said members being divided in an axial plane and open at one end
5 to admit a cord carrying a plurality of conductors, a plurality of separated contact elements mounted in the end of the outer insulating member opposed to said open end, a first set of insulated contact bands embedded in the inner wall of the
10 outer insulating member and respectively electrically connected with said contact elements, a first set of insulated contact rings mounted within the outer insulating member and seated within the first set of contact bands, a second set of in-
15 sulated contact bands embedded in the outer wall of the inner insulating member, connecting elements mounted in the outer end of the inner insulating member adapted to be connected respectively with the conductors of a cord entering
20 the outer insulating member, said connecting elements being respectively electrically connected with the contact bands of the second set, a second set of insulated contact rings mounted on the inner insulating member to bear respectively on
25 the contact bands of the second set and also to bear against the contact rings of the first set, said first set of contact rings being arranged in pairs, with the rings of each pair insulated from each other and each ring of said second set being in
30 electrical contact with one ring of said first set

but insulated from each other and adjusting means for maintaining in assembled relation the outer and inner insulating members and the parts carried thereby so that the two sets of contact rings are held in electrical contact. 5

2. A swivelling coupling for electrical conductors as claimed in claim 1, wherein the outer insulating member is divided in an axial plane into complementary parts so that separation of said parts admits the several contact bands and contact rings to be seated within the outer insulating members, and means for clamping together said complementary parts in their assembled relation, said outer insulating member being closed at the end opposite to said open end. 10 15

3. A swivelling coupling for electrical conductors as claimed in claim 1, wherein the inner insulating member is provided with an abutment at its outer end, and a detachable element mounted on the inner end of said inner insulating member coacts with the abutment to hold the assembled parts in place. 20

4. A swivelling coupling for electrical conductors as claimed in claim 1, wherein the contact rings mounted on the inner insulating member are angular in cross-section, with angularity of each of said rings registering with a corner part of the opposite contact ring mounted in the outer insulating member. 25 30

HJALMAR ASKLUND.
